UNITED STATES PATENT OFFICE

JOHN A. FLAJOLE, OF BAY CITY, MICHIGAN.

VALVE FOR FUSIBLE SAFETY-PLUGS.

SPECIFICATION forming part of Letters Patent No. 340,994, dated May 4, 1886.

Application filed January 7, 1886. Serial No. 187,937. (No model.)

To all whom it may concern:

Be it known that I, JOHN A. FLAJOLE, a citizen of the United States, residing at Bay City, in the county of Bay and State of Michigan, have invented a new and useful Improvement in Valves for Fusible Safety-Plugs, of which the following is a full, clear, and exact description, reference being had to the accompanying drawings, and to the letters and figures of reference marked thereon, which form a part of this specification.

A plug composed of metal which is fusible at a low temperature is firmly fixed into the crown-sheet or upper tubes of a boiler and arranged so that whenever the portion containing the said plug shall be above the surface of the water within the boiler the fusible plug will melt, and, running out, form an opening, which allows the steam from the boiler to rush out and put out or deaden the fire, in order to avoid the danger from an explosion caused by low water within the boiler; but often from other causes than low water in the boiler this plug becomes exposed to a sufficient degree of heat to cause its removal, and causes great inconvenience as well as danger. A boat at sea, by the action of the wind or when aground, or when pulling a heavy tow in a gale, is liable to lay over on her side and leave the plug free from a covering of water within the boiler, which allows the plug to fuse and let the water out of the boiler and put out the fires.

The object of my invention is to arrange a device by means of which the opening caused by the melting of the plug at such times may be easily and quickly closed and the water retained within the boiler, so that the vessel may be worked until the danger is passed, and thereby save the loss of life and property. I attain these objects by means of the devices illustrated in the accompanying drawings, in which—

Figure 1 is a longitudinal vertical section of a portion of a marine boiler and of my improvement thereto attached, and showing the plug in place. Fig. 2 is the same, showing the position of the parts when the plug is removed. Fig. 3 is a section at x x .

Similar letters refer to similar parts throughout the several views.

a represents the shell of a marine-boiler; b , the crown - sheet; c , the return - flues; d , the smoke-box, and e the boiler-head.

f is a plug of fusible metal, passed through the crown-sheet b and through a piece, g , which is securely fastened upon the inner side of the crown-sheet. A sliding valve, h , is placed upon the upper side of the piece g , and arranged to slide upon the surface thereof, being secured in position by the guides i . Upon the upper side of the valve h is arranged a boss, k , to which is secured in a suitable manner one end of the rod l , the opposite end of the rod being passed through the head e and a packing-box, m , which is firmly secured to the outside of the boiler-head. An extended arm, n , is secured to the packing-box, and to the outer end of the arm is pivoted one end of a lever, o , which is also pivoted, at a short distance from this pivoted end, to the outer end of the rod l , and the opposite end of the lever, after passing through the guide-piece p , is provided with a suitable handle, r . The guide-piece p is provided with holes t , into which is placed a pin for securing the lever to hold the valve in either a position for covering the plug or for leaving the plug-opening free.

The operation of the device is that when the plug is melted out and the steam and water begin to rush from the boiler the lever is pushed inward, which causes the valve to move over the plug-opening, shutting off the flow of steam and water, and then the engineer can ascertain the cause of the trouble and proceed to remove the difficulty without entirely emptying the boiler and putting out his fires, and the vessel can be run into port in this condition; whereas should the plug be melted out from any cause while in a storm the vessel is liable to go ashore before the boilers can be refilled and the steam again raised to a working pressure.

The lever and valve may be worked backward and forward from time to time to provide against sticking the valve with scale and corrosion, and the working of the valve pushes the scale and sediment from the plug, so that the water may always be in contact with the inner end of the plug, which is a great advantage, as when the plug becomes covered with sediment and scale it is liable to melt out from the action of the heat, and let the water out of the boiler when the boiler has the proper amount of water within.

Having described my invention, what I claim

as new, and desire to secure by Letters Patent, is—

1. In a fusible safety-plug valve, the combination, with the boiler and a valve-seat secured to the inside of the crown-sheet or tubes of the boiler and a fusible safety-plug passing through the crown-sheet and valve-seat, of a valve sliding upon the said seat and having square ends, whereby by the action of the valve to the sediment and scale is removed from the inner end of the fusible plug, and a rod connected with the valve and passing through the shell of the boiler, substantially as and for the purpose herein set forth.
- 15 2. In a valve for a fusible safety-plug, the combination, with the crown-sheet, the valve-seat, secured to the inside of the crown-sheet

and provided with the guides *i*, a fusible plug, *f*, passing through the crown-sheet, and valve-seat *g*, a valve, *h*, sliding upon the seat and having square ends, the rod *h*, secured to the valve and passing through the boiler-head, and the packing-box *m*, of the arm *n*, secured to the boiler, the lever *o*, pivoted to the outer end of the arm and to the valve-rod, and the guide-piece *p*, substantially as and for the purpose herein set forth.

In witness whereof I hereunto affix my signature in presence of two witnesses.

JOHN A. FLAJOLE.
